UNITED STATES PATENT OFFICE

98,182

DESIGN FOR A GASOLINE COOK STOVE

George E. Pickup, Newark, Ohio, assignor to The Wehrle Company, Newark, Ohio, a corporation of Ohio

Application November 18, 1935, Serial No. 59,638

Term of patent 3½ years

To all whom it may concern:

Be it known that I, George E. Pickup, a citizen of the United States, residing at Newark, in the county of Licking and State of Ohio, have invented a new, original, and ornamental Design for a Gasoline Cook Stove, of which the following is a specification, reference being had to the accompanying drawing, forming part thereof.

Figure 1 is a front perspective view of a gasoline cook stove, showing my new design.

Fig. 2 is a perspective view of the stove looking from one end, the opposite end of the stove being the same except for the gasoline tank and valve.

I claim:

The ornamental design for a gasoline cook stove, substantially as shown and described.

GEORGE E. PICKUP.
